(57) **CLAIM**

The ornamental design for an archery bow riser, as shown and described.

DESCRIPTION

A portion of the disclosure of this patent document contains or may contain material which is subject to copyright

protection. The copyright owner has no objection to the photocopy reproduction by anyone of the patent document in exactly the form it appears in the Patent and Trademark Office patent file or records, but otherwise reserves all copyrights whatsoever.

FIG. 1 is a front elevation view of a first embodiment of the archery bow riser.

FIG. 2 is a rear elevation view of the first embodiment of the archery bow riser.

FIG. 3 is a left side elevation view of the first embodiment of the archery bow riser.

FIG. 4 is a right side elevation view of the first embodiment of the archery bow riser.

FIG. 5 is a top view of the first embodiment of the archery bow riser.

FIG. 6 is a bottom view of the first embodiment of the archery bow riser.

FIG. 7 is a right front isometric view of the first embodiment of the archery bow riser.

FIG. 8 is a right rear isometric view of the first embodiment of the archery bow riser.

FIG. 9 is a front elevation view of a second embodiment of the archery bow riser.

FIG. 10 is a rear elevation view of the second embodiment of the archery bow riser.

FIG. 11 is a left side elevation view of the second embodiment of the archery bow riser.

FIG. 12 is a right side elevation view of the second embodiment of the archery bow riser.

FIG. 13 is a top view of the second embodiment of the archery bow riser.

FIG. 14 is a bottom view of the second embodiment of the archery bow riser.

FIG. 15 is a right front isometric view of the second embodiment of the archery bow riser; and,

FIG. 16 is a right rear isometric view of the second embodiment of the archery bow riser.

The evenly spaced broken lines in the figures represent portions of the archery bow riser that form no part of the claimed design. The uneven length broken lines in FIGS. 10, 11, 15, and 16 represent the boundary of the claim and form no part thereof.

1 Claim, 14 Drawing Sheets
